(57) **CLAIM**

The ornamental design for an oyster opener, as shown and described.

DESCRIPTION

FIG. 1 is a bottom plan view of an oyster opener showing my new design;

FIG. 2 is a top plan view thereof;

FIG. 3 is a front elevational view thereof;

FIG. 4 is a rear elevational view thereof;

FIG. 5 is a side elevational view thereof; and,

FIG. 6 is a perspective view thereof.

The broken lines showing indicia are for are for illustrative purposes only and form no part of the claimed design.
